UNITED STATES PATENT OFFICE.

CARL ELLINGSEN, OF ASHBY, MINNESOTA.

HEATER AND RADIATOR FOR STOVES.

SPECIFICATION forming part of Letters Patent No. 613,564, dated November 1, 1898.

Application filed March 15, 1898. Serial No. 673,960. (No model.)

To all whom it may concern:

Be it known that I, CARL ELLINGSEN, a citizen of the United States, and a resident of Ashby, in the county of Grant and State of Minnesota, have invented certain new and useful Improvements in Heaters and Radiators for Stoves; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a central vertical section of a heater and radiator embodying the invention. Fig. 2 is a transverse section on the line *x x*, Fig. 1.

This invention is designed to provide an improved heater and radiator for use upon stoves or in stovepipes; and it consists in the novel construction and combination of parts, all as hereinafter described, and pointed out in the appended claims.

Referring to the accompanying drawings, the letter A designates a cylinder-drum or hollow heating-body having frusto-conical end portions provided with short tubes B, whereby the drum may be interposed and fitted to adjacent sections of stovepipe. The lower end portion, however, may be fitted directly to the smoke-flue of the stove. One or both of the said end portions are usually made removable, so that the device may be readily taken apart for cleaning.

Extending centrally up through the said drum is an inner tube or cylinder L, open at both ends and which is removably secured in the orifice which leads to the lower tube B. Said tube is formed at intervals with openings D through its walls, said openings being arranged in regular horizontal or circumferential lines or series and those of one line or series alternating in position with respect to the openings of adjacent series. To form these openings, the metal of the tube or cylinder is not entirely removed, but is left uncut at the top, and these tongues of metal so formed and indicated at E are in the respective series bent alternately outward and inward. Those tongues which are bent out-

wardly form supports for downwardly-inclined annular deflector-plates H, which are of slightly less diameter than the internal diameter of the drum or cylinder A. Hung 55 in the upper portion of the tube or cylinder is a damper F, whose rod F' extends out through and rests in a slot f in the upper portion of the drum or cylinder A. This damper is arranged to entirely close the outlet at the 60 top from the said tube into the upper portion of said cylinder. Hung in the upper tube B is a second damper G, carried by a rod G'. This damper has an opening g therethrough.

Hot air, smoke, and gases of combustion 65 rising into the tube C are deflected outwardly through the openings D by means of the inwardly-bent tongues, and passing out through the openings are brought into contact with the wall of drum A by means of the deflector- 70 plates H.

By regulating the damper F all the heat, smoke, and gases, or such a portion thereof as may be desired, may be caused to pass out through the said openings, and by regulating 75 the damper G the same may be held in the drum for a longer or shorter time.

I do not wish to limit myself to the precise construction herein shown and described, as the same may be varied somewhat without 80 departing from the spirit and scope of my invention.

Having thus described my invention, what I claim as new, and desire to secure by Letters Patent, is—

1. In a heating-drum and radiator, the combination with an outer shell or cylinder having an inlet at one end portion, and an outlet at the other end portion, of the inner tube or cylinder open at both ends and communicating 90 respectively with the said inlet and outlet, said tube having portions of its metal partially cut out to form openings, a number of said portions being bent outwardly, and the rest inwardly, and a series of deflector- 95 plates supported on the outwardly-bent portions, substantially as specified.

2. In a heating-drum and radiator, the combination with an outer shell or cylinder having an inlet at one end portion, and an outlet at the other end portion, of an inner tube or cylinder open at both ends and communi- 100

eating respectively with the said inlet and outlet, said tube having portions of its metal partially cut out to form openings, a number of said portions being bent outwardly and 5 the rest inwardly, and a series of deflector-plates supported on the outwardly-bent portions, together with dampers one in the outlet to the outer cylinder, and a second in the upper portion of the inner tube or cylinder,

above its said openings substantially as speci- 10 fied.

In testimony whereof I affix my signature in presence of two witnesses.

CARL ELLINGSEN.

Witnesses:
